Isaac Knapp.

UNITED STATES PATENT OFFICE.

ISAAC KNAPP, OF MEDINA, NEW YORK.

IMPROVEMENT IN STOP-DAMS FOR CANALS.

Specification forming part of Letters Patent No. 35,242, dated May 13, 1862.

To all whom it may concern:

Be it known that I, ISAAC KNAPP, of the village of Medina, in the county of Orleans and State of New York, have invented a new and Improved Stop-Dam and Gates and Gage-Gates to Dam Up and Stop the Water in Canals and Artificial Water-Courses and to Gage and Regulate the Water Therein; and I do hereby declare that the following is a full and exact description.

The nature of my invention consists in providing a structure which may be readily moved across a canal or artificial water-course at right angles with the prism, reaching from bank to bank or side to side and faced or ceiled on its outer sides with plank from the top of the structure down to as near the bottom as may be thought prudent, and all the space below the ceiling is to be closed by means of gates, which are to be raised or let down by means of screws, that when such structure is placed across the canal or artificial water-course and the gates closed it will effectually dam up and stop the flow of water, and by placing the gates at any desired elevation and ceiling up below and raising and letting them down by means of the screw, as aforesaid, the height of the water may be regulated and fixed and any desired depth secured, and the gage-gates, detached from the stop-dam, can be used profitably and with advantage in the construction of waste-weirs.

To enable others skilled in the art to make and use my invention, I will proceed to describe its construction and operation.

I construct my structure by having two parallel rows of posts of suitable height, standing a little inclined inward from a perpendicular, being inclined from the base upward and inward. The posts are set equidistant from each other, and the entire length of the structure is the width of the channel where it is to be used. Each line of posts is framed together by a sufficient number of parallel girts, the number depending upon the height and magnitude of the structure. These parallel rows of posts are to be put at a suitable distance apart and framed substantially together by means of cross-beams and braces, one beam being framed and placed at the top of the posts and the other near the bottom, and two braces used between each two oppo-

site posts, each being framed into one and the other in the other of the angles formed by the posts and lower cross-beams, and then running diagonally across and being framed into the upper angles formed by the posts and upper cross-beams. The upper cross-beams are to project beyond the posts a sufficient distance to receive and support the plates, and upon them is to be placed on each side a plate running lengthwise thereof and extending from one end to the other of the structure. Commencing on each outer side of the structure, at a proper height from the bottom thereof, the same is to be planked or ceiled from such point down to within such distance from the bottom as may be thought advisable, everything being taken into consideration in determining where the planking or ceiling shall stop. The entire space below is to be closed by means of gates, which are to be raised and lowered by the use of screws thereto attached, being connected with a swivel or similar connection, so as to render them perfectly serviceable in the use intended.

The gates are to be kept open while moving the structure across a canal or artificial water-course to relieve the stop-dam from the pressure of water in part and closed when placed in position. The gates, raised and lowered in the manner above indicated, may also be used in constructing waste-weirs to regulate the depth of water in canals and artificial water-courses.

The stop-dam and gates, when constructed and complete in the manner hereinbefore specified, are to be used in the following manner: If in a canal, an opening is to be cut into the berme-bank, of the same length as the canal is wide, then heavy ties are to be firmly embedded into the canal bottom and side opening, and then there is to be placed across the canal and into the side opening, at right angles with the ties, two mud-sills having their upper sides on a level with canal bottom and their inside faces protected by iron bars or straps strongly bolted to the timber. Immediately on the inside of the mud-sills are to be placed rails forming a track for the structure or stop-dam and gates like a railroad-track. Then in the bottom of each of the posts in the structure is to be fixed a strong iron wheel, and adjusted to the track

aforesaid, and at each end of the structure and on each side is to be placed diagonally an iron plate to clear the track of obstructions.

When the structure is complete, it is to be placed upon the track, formed as aforesaid, and is to be moved across the canal and into the side cut by means of a rope, pulley, and capstan, the wheels resting upon the track.

On the drawings the ties are indicated by the letter *a*, the mud-sills by the letter *b*, the track by the letter *c*, the posts by the letter *d*, the wheels by the letter *e*, the girts by the letter *f*, the cross-beams by the letter *g*, the

braces by the letter *h*, the plates by the letter *i*, the ceiling by the letter *j*, the gates by the letter *k*, the joints in the gates by the letter *l*, the swivels by the letter *m*, the screws by the letter *n*, and the scrapers by the letter *o*. What I claim as my invention, and desire to secure by Letters Patent, is—

The structure hereinbefore described, and the mode or manner of using the same, as hereinbefore explained.

ISAAC KNAPP.
